UNITED STATES PATENT OFFICE.

OMAR N. GARDNER, OF JAMESTOWN, NEW YORK.

OPERATING AND DETACHING MECHANISM FOR EXCAVATING BUCKETS.

Application filed November 18, 1921. Serial No. 516,082.

To all whom it may concern:

Be it known that I, OMAR N. GARDNER, a citizen of the United States, residing at Jamestown, in the county of Chautauqua and State of New York, have invented certain new and useful Improvements in Operating and Detaching Mechanism for Excavating Buckets, of which the following is a specification.

10 My invention relates to operating and detaching mechanism for excavating buckets and the like, and has particular reference to an attachment for "clam shell" or "orange peel" buckets of the double line type to permit the ready and expeditious attachment and detachment of such buckets to and from the hoisting and holding lines of such apparatus.

It is a well known fact among engineers and contractors employed in excavating and hoisting operations, that it is often desirable and necessary to detach the excavating buckets from the crane or derrick when it is desired to employ the same for other hoisting purposes. With the form of buckets now in use, this detaching or disconnecting operation necessitates the removal of bolts and a partial disarrangement of the bucket structure and the reeving off 20 of the cable from the bucket operating mechanism, thus consuming a considerable period of time and a consequent delay in the work. The almost universal use of excavating buckets on contract work has created a demand for a quick-detachable bucket, especially in that form of hoisting and excavating buckets employing double lines, one for operating and hoisting the bucket and the other for holding the same in its 30 suspended position.

An object of this invention is to provide an attachment for excavating buckets of the double line type, especially those of the "clam shell" or "orange peel" variety, that will permit the detachment of the bucket from the lines in the minimum period of time and which will not require the removal of bolts or disarrangement of the bucket structure.

40 A further object of the invention is to provide a device of this general character that is capable of attachment to the double line buckets now in general use, and which will not require change or alteration in their present construction or operation.

A further object of this invention is to

provide a drum adapted for attachment to the top of the bucket which functions in the bucket's operation, and by means of which the bucket can be quickly detached from the holding and hoisting lines of the crane or derrick.

A still further object of this invention is to provide a device of the above mentioned character that is simple in construction, convenient in use, and strong and durable.

In the accompanying drawings, forming a part of this specification and in which like numerals are employed to designate like parts throughout the several views,

Fig. 1 is a side elevation of an excavating bucket provided with my improved form of detaching mechanism, showing the bucket in closed position;

Fig. 2 is an enlarged side view of the detaching drum showing the relative position of the hoisting and operating line on the compartments of the drum when the bucket is in open position;

Fig. 3 is an end view of the drum, showing the hook and slot members;

Fig. 4 is a side elevation of a bucket provided with my improved form of detaching mechanism showing the bucket in open position;

Fig. 5 is a fragmental horizontal sectional view of my improved drum; and

Fig. 6 is an enlarged end view of my improved attachment.

In the present instance, by way of illustration, I have shown my invention as employed in connection with a clam shell bucket of the well-known "Hayward" type, but I wish it to be understood that the invention is not limited to the particular application but is equally well adapted to all forms of "clam shell" and "orange peel" buckets of the double line type.

Referring to the drawings, wherein for the purpose of illustration is shown a preferred embodiment of my invention, the numerals 1-1 designate the coacting sections of a clam shell bucket, carrying the arms 2-2 which are pivotally mounted on a central shaft 3. Rigidly secured on the shaft 3 at the central portion thereof is a power wheel 4 to which is secured the bucket operating line 5. The operating chains of the bucket sections are indicated at 6-6, said chains having their upper ends rigidly secured to a cross bar 7 and their lower ends secured to the shaft 3 at opposite sides of

the power wheel 4. The coacting bucket sections 1—1 have their outer corners pivotally connected to the cross bar 7 by means of suitable brace rods 8—8. All of the above 5 construction is conventional and well known in the art and forms no part of my present invention.

The construction and operation of the bucket will, it is thought, be obvious from 10 the foregoing description. Assuming that the bucket is closed and suspended above the load it is desired to convey, it is only necessary to slacken the bucket operating line 5, and the relatively heavy shaft 3 and 15 its connected parts will drop downwardly and thrust the bucket sections apart through the agency of the arms 2—2. In descending, the power wheel 4 is rotated by the resistance afforded by the unwinding of the chains 20 6—6 and simultaneously winds up in an opposite direction the bucket operating line 5 within the peripheral groove of the power wheel 4. In closing the bucket, lifting power is applied to the line 5 and shaft 3 25 to wind the chains 6—6 thereon to draw the arms 2—2 upwardly and close the bucket sections together.

Detachably connected to the upper portion of the cross bar 7 by means of suitable 30 connecting links 9 is a substantially rectangular frame 10 having rotatably journaled between the vertical sides thereof a drum 11. This drum is provided with radially extending end flanges 12 and 13 and 35 is divided throughout its length into three separate and distinct compartments 14, 15 and 16 by means of the partition flanges 17 and 18. Each of the end flanges 12 and 13 is provided with radial slots 19 and at 40 points diametrically opposite said slots with hooks 20. Partition flange 18 is also provided with a radially extending slot 21 for allowing the passage of the bucket operating line 5 from one compartment to another 45 as will be hereinafter explained.

Extending outwardly from the vertical side bars of the frame 10, in a plane slightly above the periphery of the drum 11 are the cross pieces 22 and 23, having their inner 50 ends held in spaced relation to form an opening 24 through which the operating line 25 may pass when reeled off the compartment 14. This opening is normally closed by means of the plate 26 pivotally mounted 55 on the cross piece 22, and which is provided with the roller 27 which effectively coacts with a parallel roller 28 slightly in rear thereof to prevent abrasion of the operating and hoisting line 25 as it is reeved between the 60 same. The inner spaced ends of the cross pieces 22 and 23 are provided with parallel 65 guide rollers or sheaves 29 and 30 which are disposed at right-angles to the rollers 27 and 28 and serve as guide members to properly 70 align the cable or line in its movement there-

between. The holding line 31 from the crane or derrick has secured at its lower end the hook 32 which is detachably connected to the central portion of the upper side of the frame 10. This hook is held in its engaged 75 position by means of the counterweighted pivoted lever 33 which in its normal position prevents the hook from becoming detached from this cross piece of the frame.

The method of reeving the ropes upon the 75 various compartments of the drum 11 to accomplish the hoisting and bucket operations, and the manner of attaching and detaching the bucket to and from the hoisting and holding lines is as follows. The bucket is opened 80 to the full extent of its spread and the hook 32 engaged and locked to the upper cross piece of the frame 10 by means of the counterweighted lever 33. The end of the operating and hoisting line 25 is formed 85 into an eye or loop as shown in the drawings, and is reeved through the opening 24, through the slot 19 in the outer flange 12 and secured to the hook 20. The drum is then 90 rotated by hand to wind the line 25 onto compartment 14, a sufficient amount of line being wound on this compartment to allow for the playout of the bucket during the closing operation and also an extra 95 amount equal to about three complete wraps. The bucket operating line 5 has its upper end provided with a suitable eye which engages the hook 20 on the outer flange 13, the line then passing through the radial slot 19 and making a complete turn about the compartment 16. This line then passes through the slot 21 in the partition plate 18 and on to compartment 15 from which it depends to the power wheel 4. The hoisting engine 100 of the crane or derrick is then started and pulls on the operating and hoisting line 25, thus unwinding the line from compartment 14 and at the same time winding the bucket operating line 5 upon compartment 15 thus 105 closing the jaws 1—1 of the bucket about the load as above explained. The bucket is then hoisted to the required height by the hoisting and operating line 25, the weight is then shifted to the holding line 31, and the line 25 slackened. The downward pull 110 on the bucket operating line 5 caused by the weight of the load and the shaft 3 and its connected parts will cause the line 5 to unwind from compartment 15, thus winding the operating and hoisting line 25 upon the 115 compartment 14. The open bucket is then lowered on the holding line 31 to the place of loading.

Where it is desired or necessary to detach the bucket and operating drum from the hoisting and holding lines 25 and 31 respectively, the bucket may be lowered to the ground in open position, the friction is then thrown off the hoisting line drum of the hoisting engine of the crane or derrick and 120 125 130

the hoisting line 25 is pulled slack so that the detacher drum 11 may be readily revolved. The bucket operating line 5 is then pulled to unwind the line from compartments 15 and 16 and, when completely unwound, the eye at the upper end of said line is disengaged from the hook 20 on the end flange 13. The hoisting engine is then started to raise the hoisting line 25. This movement causes the line 25 to unwind from compartment 14 and when completely unwound therefrom, the end of the line is readily disengaged from the hook 20 on the end flange 12, thus disconnecting the hoisting and operating line 25 from the bucket structure. The counterweighted lever 33 is then moved about its pivot and the hook 32 on the holding line 31 is disengaged from the cross frame of the detaching mechanism. In the above description of the method of attaching and detaching the bucket, I have mentioned that the bucket is lowered to the ground in open position, but this is not essential to the successful operation of the detacher and the same may be attached and detached to and from the lines when the bucket is resting on the ground in closed position.

It is to be understood that the form of my invention herewith shown and described is to be taken as a preferred example of the same and that various changes in the shape, size and arrangement of parts may be resorted to without departing from the spirit of the invention or the scope of the appended claims.

Having thus described my invention what I claim as new and desire to secure by Letters Patent is:—

1. A device of the character described comprising an excavating bucket having a power wheel, hoisting and holding lines for operating said bucket, an attachment secured to said bucket, independent of said power wheel, to which said hoisting and holding lines are detachably fixed, and means connecting said attachment to said power wheel whereby upon the hoisting or lowering of said bucket said power wheel is rotated to close or open said bucket.
2. A device of the character described comprising an excavating bucket having a power wheel, hoisting and holding lines for said bucket, an attachment including a rotatable drum secured to said bucket independent of said power wheel, to which said hoisting and holding lines are detachably fixed, said hoisting line being attached to said drum for winding and unwinding thereon and a bucket operating line secured at one end to said power wheel and at the other end to said drum whereby upon winding or unwinding of the hoisting line on said drum, said power wheel is rotated to close or open said bucket.
3. A device of the character described,

comprising an excavating bucket having a power wheel, hoisting and holding lines for said bucket, and an attachment including a rotatable drum secured to said bucket independent of said power wheel, to which said hoisting and holding lines are detachably fixed, said hoisting line being attached to said drum for winding and unwinding thereon, and means connecting said drum to said power wheel whereby upon winding or unwinding of the hoisting line on said drum, said power wheel is rotated to close or open said bucket.

4. A device of the character described comprising an excavating bucket, a rotatable drum secured to the bucket and having end flanges provided with radial slots, a hoisting line secured to one end of the drum and passing through the radial slot therein and wound upon the drum, a bucket operating line secured to the opposite end of the drum and passing through the radial slot therein and wound upon the drum in a direction opposite to the winding of the hoisting line, and means for causing the winding and unwinding of the respective lines about the drum to effect the opening and closing of the bucket.

5. A device of the character described, comprising an excavating bucket, a rotatable drum secured to the bucket, said drum having end flanges and being divided axially into separate peripheral compartments, a hoisting line secured to one end of the drum and wound about one end compartment, a bucket operating line secured to the opposite end of the drum and wound about the adjacent end compartment and onto an intermediate compartment in a direction opposite to the winding of the hoisting line, and means for causing the rotation of the drum to effect the opening and closing of the bucket.

6. A device of the character described, comprising an excavating bucket having a power wheel, an attachment including a rotatable member secured to said bucket independent of the power wheel, a hoisting line detachably secured to said rotatable member and wound about the same, a bucket operating line detachably secured at one end to the rotatable member and wound about the same in a direction opposite to that of the winding of the hoisting line, and secured at the other end to and wound about said power wheel whereby said winding and unwinding of the hoisting line actuates said power wheel and connections between said power wheel and bucket whereby the rotation of said power wheel in one direction closes said bucket, and in the other direction opens said bucket.

7. A device of the character described comprising an excavating bucket; a rotatable drum secured to the bucket, said drum

- being divided axially into separate peripheral compartments; a hoisting line secured to the drum and wound about one compartment thereof for a length slightly greater than the play-out of the line when the bucket is in open position; a bucket operating line secured to the drum and adapted to be wound about a central compartment of the same for a length substantially equal to the play-out of the line when the bucket is in open position and having an additional length equal to one complete wrap about the drum passing over to the remaining compartment of the drum; and means for causing the rotation of the drum to alternately transfer this play-out from one compartment to the other to effect the opening and closing of the bucket.
8. A device of the character described comprising an excavating bucket, a rotatable drum secured to the bucket, a hoisting line secured to the drum and wrapped about the same for a length slightly greater than the play-out of the line when the bucket is in open position, a bucket operating line secured to the drum and of slightly greater length than the play-out of the line when the bucket is in open position, and means for unwinding the hoisting line and winding the bucket operating line upon the drum to close the bucket.

9. An attachment for an excavating bucket of the double line type including a rotatable drum divided axially into three peripheral compartments, an operating line connecting said drum with said bucket, said line being detachably secured to one end of said drum, wound around said drum in the compartment adjacent that end, passed through the division into the middle compartment and wound around said drum in said middle compartment before being connected to said bucket, the bucket hoisting line being detachably secured to the other end of said drum and wound around the same a plurality of turns in the direction opposite to that of said operating line and the bucket holding line being detachably secured to said attachment.

10. An attachment for an excavating bucket of the double line type including a rotatable drum, and an operating line detachably secured to said drum and connected to the bucket opening and closing mechanism, the bucket hoisting line being detachably secured to said drum and the bucket holding line being detachably secured to said attachment.

In testimony whereof I hereunto affix my signature.

OMAR N. GARDNER.
